UNITED STATES PATENT OFFICE.

JOHN STURROCK, OF CHICAGO, ILLINOIS, ASSIGNOR TO INTERNATIONAL HARVESTER COMPANY, OF CHICAGO, ILLINOIS, A CORPORATION OF NEW JERSEY.

PITMAN CONNECTION.

Application filed March 13, 1922. Serial No. 543,212.

My invention relates to pitman connection especially adapted for mowers and like machines.

The object of the invention is to provide means whereby the wear between the pitman and the associating or co-operating parts of the machine on which the pitman is used is automatically compensated for, and the parts at all times are held in proper adjustment.

A further object is to provide means for easily and quickly connecting the pitman to the parts co-operating therewith, and disconnecting the pitman from said parts.

A still further object is to provide a pitman connection in which the number of movable parts are reduced to a minimum.

These and other objects are attained by the use in connection with pitman straps of a clamping member by means of which these straps are forced toward each other or separated from each other, and further by the use of a crank member in connection with the clamping member the latter is prevented from becoming accidentally unclamped while in its clamping position.

Referring to the accompanying drawings, I have for the purpose of illustration shown one embodiment which my invention may assume in practice.

In the drawings, wherein like characters represent the same parts throughout the several views.

Fig. 1 is a plan view of the stubbleward end of a pitman embodying my improvement;

Fig. 2 is a side elevational view of Fig. 1;

Fig. 3 is an elevational view partly in section showing the clamping member in its inoperative position; and

Fig. 4 is a plan view partly in section showing the clamping member in its inoperative position.

The pitman illustrated in connection with the showing of my invention embodies two pitman straps 11 and 12, the strap 12 being resilient and the strap 11 preferably made resilient, although not necessary for the successful operation of the construction. The straps 11 and 12 are secured to the wood portion 13 of the pitman by means of a series of rivets 14. The grassward end of the pitman straps 11 and 12 are provided with the

usual spoon or cup-shaped bearing portions 15 and 16 respectively, which are adapted to receive and form the connection with the spherical portion formed on the knife head.

The outer surfaces of these portions 15 and 16 are provided with beveled surfaces 17 and 18 for the purposes hereinafter set forth.

Adjacent these beveled surfaces 17 and 18 and extending longitudinally with respect to the straps 11 and 12 are elongated slotted apertures 19 and 20, which terminate in oppositely disposed corresponding beveled surfaces 21 and 22 in the straps 11 and 12 respectively.

Positioned between the straps 11 and 12 adjacent the grassward end of the wood portion 13 are two enlarged bearing portions 23 and 24 provided with registering apertures 25 and 26 adapted to pivotally receive a crank member 27.

The crank member 27 is provided with a laterally extending arm 28, which in turn is provided with oppositely disposed wings or projections 29 which are adapted to engage the edges of the straps 11 and 12, as shown in Fig. 2, in the normal operation of locking the clamping member.

The arm 28 of the crank 27 is provided with a slotted aperture 30 adapted to slidably receive the stubbleward end 31 of a clamping member 32.

The clamping member 32 is slidably secured in the slot 30 of the arm 28 by means of a pin 33. The stubbleward end 31 of the clamping member 32 is provided with a slot 37, which permits the clamping member 32 to reciprocate with respect to the crank 27 and contact an abutment or shoulder 27' thereon (see Fig. 3)

when the clamping member is in clamping position and thereby lock the parts in position to prevent accidental unclamping thereof.

The crank 27 is further provided with a square shank portion 34 adapted to receive a wrench or other tool for manipulating the clamping member. Adjacent the pin 33 and formed as an integral part of the crank 27,

is a cam portion 35 and a flat shoulder portion 36 for the purpose hereinafter set forth.

The clamping member 32 is provided with two fork-extending portions 38 and 39, which in turn are provided with oppositely diverging surfaces 40 and 41 adapted to engage the beveled surfaces 17 and 18 respectively for clamping the straps 11 and 12 to

the knife head of the mower. Similarly, the clamping member 32 is provided with stubblewardly inclined surfaces 42 and 43 adapted to engage the inclined surfaces 21 and 22 of the straps 11 and 12 in the normal operation of spreading or separating the straps 11 and 12 and disconnecting the pitman from the knife head of the mower. This is accomplished by swinging the crank 27 to the position shown in Fig. 3, withdrawing the clamping member 32 from the surfaces 17 and 18 and spreading the straps by forcing the clamping member to the position shown in Fig. 4.

15 The clamping member 32 is provided with an angularly disposed shank 44, which in turn carries a spring 45. The grassward end of the spring 45 is normally held in contact with the clamping member 32 by means of an enlarged or collar portion 46. The stubbleward end of the spring 45 is supported on the cam surface 35 of the crank 27 by means of a washer 47, as shown in Fig. 3. It will be noted that as the crank 25 is thrown from the position shown in Fig. 3 to the position shown in Fig. 2 that the washer 47 will ride over the cam surface 35 and engage the shoulder 36, locking the crank 27 in the position shown in Fig. 2 with 30 the projections 29 engaging the sides of the straps 11 and 12. In this locked position it will be noted that the clamping member 32 may be reciprocated within the limits of the slot 37. That is, the member 32 may 35 be moved stubblewardly in a manner to compress the spring 45 until the grassward end of the slot 37 strikes the pin 33 and thus prevents the accidental unclamping or spreading 40 of the straps 11 and 12.

40 It will be further noted by the construction above described, in which the clamping member is provided with an angularly bent shank 44, that an extra movable part has been eliminated and that a very efficient and 45 compact automatic pitman, which can be easily clamped and spread quickly, has been designed.

While I have in this application specifically described but one embodiment which 50 my invention may assume in practice, it is of course to be understood that my invention is not limited to the specific form shown herein but may be modified to assume other forms without departing from the spirit and 55 scope of my invention, it being my intention to include all such forms within the scope of the appended claims.

What I claim as my invention and desire to secure by Letters Patent is:

1. In a pitman connection, a pitman having resilient straps, said straps having registering slots, a clamping member having a shank rigidly fixed thereto and at an angle to the plane thereof, said member being adapted to protrude through said straps and slidably engage said straps, said member having therein a walled slot, a crank member pivoted to said straps and connected to said clamping member, a spring disposed between said crank and said clamping member, and means including the walls of the slot in said clamping member for limiting the yielding movement of said clamping member and preventing the accidental spreading of said straps. 75

2. In a pitman connection, a pitman having resilient straps, said straps having registering slots, a clamping member adapted to protrude through said slots and slidably engage said straps, said clamping member having a shank rigidly fixed thereto and at an angle to the plane thereof, a crank member pivoted to said straps and connected to the shank of said clamping member, a spring surrounding said shank and disposed between said crank and said clamping member, and means forming a part of said clamping member for clamping and spreading said straps. 80

3. In a pitman connection, a pitman having slotted resilient straps, a clamping member having a shank rigidly fixed thereto and at an angle to the plane thereof, said member being adapted to protrude through the slots in the straps, a crank carried by the straps and having a shoulder portion adapted to actuate the clamping member, and means causing the clamping member and shoulder portion on the crank to abut whereby accidental unclamping of the straps is prevented. 90

4. In a pitman connection, a pitman having resilient straps, a clamping member for the straps, said member having a shank rigidly fixed thereto and at an angle to the plane thereof, a crank having a shoulder portion pivoted between the straps, and a sliding pivotal connection between the member and crank whereby said member will abut the shoulder on the crank when the parts are in clamping position to prevent accidental unclamping thereof. 105

In testimony whereof I affix my signature.
JOHN STURROCK.
